(57) **CLAIM**

The ornamental design for a breathing apparatus for an anesthesia machine, as shown and described.

DESCRIPTION

FIG. 1 is a front view of a design for a breathing apparatus for an anesthesia machine.

FIG. 2 is a back view of the breathing apparatus for an anesthesia machine.

FIG. 3 is a left side view of the breathing apparatus for an anesthesia machine.

FIG. 4 is a right side view of the breathing apparatus for an anesthesia machine.

FIG. 5 is a top view of the breathing apparatus for an anesthesia machine.

FIG. 6 is a bottom view of the breathing apparatus for an anesthesia machine.

FIG. 7 is a front-left perspective view of the breathing apparatus for an anesthesia machine; and,

FIG. 8 is a back-right perspective view of the breathing apparatus for an anesthesia machine.

The solid lines in FIGS. 1-8 illustrate a breathing apparatus for an anesthesia machine according to the present invention. In the drawings, the dash-dot broken lines are for the purpose of illustrating environment only and form no part of the claimed design. The dash-dot-dot broken lines shown in FIG. 6 indicate surfaces of the breathing apparatus for an anesthesia machine that form no part of the claimed design. In FIGS. 6 and 8 the dash-dot-dot broken lines represent the bounds of the claimed design and form no part of the claimed design.

1 Claim, 8 Drawing Sheets
